INVENTOR

UNITED STATES PATENT OFFICE.

FRITZ LEOPOLD SCHMIDT, JR., OF NEW YORK, N. Y.

POCKET ELECTRIC BOOK LAMP.

Application filed August 2, 1924. Serial No. 729,848.

This invention relates to portable electric lamps and particularly to that type which can be carried about on the person and which is readily attachable to a small article, such as a book cover for concentrating the light from the lamp at any desired point.

My invention contemplates the provision of a reading lamp which may be easily carried about the person, a substantial though light frame for supporting the lamp and enclosing the wires thereto, a suitable base by which the lamp may be attached at any desired projecting surface, such as, the cover of a book, and terminals which may be readily connected electrically and physically to the usual flat prong terminals of a pocket battery.

The various objects of my invention will be clear from the description which follows, and from the drawings, in which—

Fig. 1 is a front elevation of the preferred form of my invention.

Fig. 2 is a side elevation of the same.

Fig. 3 is a perspective view of one of the terminal connections by means of which current is conducted to the lamp, and

Fig. 4 is a similar view of the other terminal.

In the illustrated embodiment of my invention I provide a base *b*, preferably rectangular in cross-section, of sufficient length to be readily attachable to a spring clip of any of the conventional types in a manner described more fully hereinafter. Preferably U-shaped clamps as *a*, having a lower leg *a'* and an upper leg *a''* are secured preferably over the ends of said base by means of the thumb screws *c* passing through the upper leg *a''* and the base *b*, the under surface of the leg *a''* being arranged to engage the upper surface of the base *b*. The upper surface of the leg *a'* of the clamp member *a* is adapted to engage one of the surfaces of the clip aforementioned, and the under surface of the base *b* is adapted to engage the opposite surface of said clip, whereby said clip is removably secured in place between the under surfaces of said base *b* and the upper surface of said leg *a'*.

A rigid frame preferably of brass tubing is provided for supporting a suitable lamp, said frame being preferably made substantially L-shaped in form for easy carrying about in the pocket of the user, and comprising two substantially parallel members, *d* and *h*, the member *d* being preferably of

greater length than the member *h*. A third frame member *f* preferably of the same material as that of the members *d* and *h* is operatively connected to said members by means of the right angle elbows *e* and *g* respectively. One end of the frame member *h* is secured to the elbow *g* while the other end is suitably fastened into the swivel connection *i* of the usual type for allowing adjustment of the lamp at any angle within the limits of said connection.

The lamp *z* is secured in a socket *j* of any of the conventional types, which socket is, in turn, connected to the lower member of the swivel connection *i*. Current is supplied to said socket and therethrough to the lamp by means of suitable wires not shown entering the frame member *d* through a suitable opening as *n* through the lower end thereof, entirely enclosed by and concealed in said tubing, and passing through said tubing to the usual connections in the socket *j*. One of said wires terminates in the battery connection *o* which is preferably made of sheet material, and which has an opening *p* near one end thereof in which the conducting wire may be readily secured. Said terminal *o* has a portion *o'* bent back on itself and spaced from the remainder of the terminal a sufficient distance to allow the flat sheet metal terminal prong of the usual small pocket battery to be inserted therebetween in intimate contact with the battery terminal. The other conducting wire is connected to the terminal *q* preferably U-shaped and having an opening *r* near the closed portion thereof, through which the end of the conducting wire is passed. The second battery terminal prong is passed between the branches of the U and makes quick, slideable, but intimate contact with said branches. It will be understood that there is sufficient spring action in the terminals *o* and *q* to cause said terminals to engage the battery terminal prongs without danger of becoming loose or slipping off therefrom.

The operation in my improved device is as follows: The thumb screws *c* are loosened sufficiently to allow the insertion over the legs *a'* thereof of a spring clip after which said screws are tightened to secure said clip in place. The entire device is then ready to be attached to a flat object as, for instance, the cover of a book in proper position and the lamp may be adjusted to cast its light directly on the page to be read. When the

use of the device is to be discontinued one or both of the terminals *o* and *q* may be slipped off the battery terminal and the entire device carried in the pocket until it is found to be needed.

It will be seen that my improved device is of rigid, substantial construction while allowing adjustment thereof to the proper position to cast light on the desired point. 10 It will further be seen that my device is small enough and of suitable shape to be readily carried about, that it is inexpensive to manufacture and efficient in its operation.

I do not wish to be understood as limiting myself to the specific features illustrated and described as it will be understood that various changes may be made in the construction shown without departing from the spirit of my invention as indicated in the 15 appended claim.

I claim:

In a pocket electric book lamp, a rigid tubular L-shaped frame comprising a pair of hollow members arranged in parallel 25 relation, one of said members being longer than the other, the longer of said members having an opening spaced above the lower end thereof, a third hollow frame member substantially perpendicular to said parallel 30 members, an elbow at each end of said third

member joining said third member to said parallel members, and adapted to receive wires passing through said opening and through said hollow members to the extremity of the shorter of said parallel members, a swivel joint at the extremity of the shorter of said parallel members, a lamp socket at the end of said joint to which said wires are connected, means at the extremity of the longer of said parallel frame 35 members for removably securing said frame to another article comprising an elongated, substantially rectangular base rigidly secured at the center thereof and at right angles to said longer frame member, a removable U-shaped clamp covering each end of said base, said clamp comprising a pair 40 of substantially parallel legs and a web joining the outer ends of said legs, said legs being spaced apart to allow the passage 45 of a thin object between the under face of said base and upper faces of the lower legs, and a screw passing through each of the upper legs of the clamps and through said base whereby a spring clip or a book cover 50 may be inserted between said base and the lower legs of the clamps and secured in place by the movement of said screw.

FRITZ LEOPOLD SCHMIDT, JR.
